UNITED STATES PATENT OFFICE.

HOMER C. BOSTIAN, OF EAST ROCHESTER, NEW YORK, ASSIGNOR OF ONE-FOURTH TO JEROME N. MARSHALL, ONE-FOURTH TO WILLIAM J. SHEEHY, AND ONE-FOURTH TO EMILY W. JOYCE, ALL OF EAST ROCHESTER, NEW YORK.

RAIL-DRILLING APPARATUS.

Application filed April 2, 1923. Serial No. 629,236.

To all whom it may concern:

Be it known that I, HOMER C. BOSTIAN, a citizen of the United States of America, residing at East Rochester, in the county of Monroe and State of New York, have invented certain new and useful Improvements in Rail-Drilling Apparatus, of which the following is a specification.

The object of this invention is to provide a machine for drilling the holes into the web of the rails of a railroad track in which holes the tie rods of the track are anchored.

Another object of this invention is to so construct this machine that it can be fastened to and adjusted on the rail on the outside of the track after the track is laid so that the drilling operation can take place while cars run over the track.

With this machine holes can therefore be drilled into the rails during the repair of a track or the laying of a new track without the interruption of the car service over the track during the drilling operation.

In the accompanying drawings:

Figure 1 is a front elevation of the drilling machine.

Figure 2 is a top plan view of the machine.

Figure 3 is a side elevation of the machine.

In the several figures of the drawings like reference numerals indicate like parts.

The present practice for drilling the holes into the web of rails of railroad tracks after the track has been laid is to anchor a drilling apparatus between the two rails of the track or on top of the track and proceed to drill the holes until the drilling interrupted by a car that is ready to run over the track at the point where the drilling operation takes place. The drill must then be removed to let the car pass. The car service is thus held up while the drilling operation takes place and when the drilling apparatus is removed to let the car pass the drilling operation is interrupted. In this way the laying of the track as well as the car service over the track is delayed by the drilling of the holes into the web of the rails.

This delay is eliminated with the use of

the drilling machine forming the subject matter of my present invention, as this machine is built in a manner that permits it to be clamped to the rail to be drilled on the outside of the track. The operator of the drilling machine can, therefore, use the drilling machine and drill holes while cars run over the track that is being drilled.

This machine, as illustrated in the figures of the drawings, is built up of the bed plate 1 having the supporting arm 2 projecting out on one side thereof. This supporting arm is located intermediate of the bed plate and forms an integral part thereof. On the under side it is reinforced by the ribs or flanges 3 and 4, which also form an inverted channel on the under side of the arm in which the movable clamping member 5 is mounted to slide.

On the outer end of the arm at the top thereof is formed the jaw 6 which is adapted to engage one edge of the base of the rail on which the machine is to be supported. A pair of jaws 7, 7 are formed on the end of the movable clamping member 5. These are located opposite to the jaw 6 on top of the supporting arm 2. For this purpose the arm 2 is provided with the openings 8, 8 through which the jaws 7, 7 of the movable member 5 project to slide back and forth 80 therein.

Fastened to the under side of the arm 2 between the ribs 3 and 4 is mounted the bearing block 9 and in line with this bearing block on the under side of the bed plate 1 is provided a second bearing block 10. These two bearing blocks support the clamping screw between them and allow it to be turned by means of a wrench at the front or back of the machine. For this purpose the outer ends of the screw 11 have a square head formed thereon that can be readily taken hold of by the wrench.

The screw 11 is threaded into and passes through the boss 12 formed on the under side of the clamping member 5. This engagement of the screw with the clamping member provides for the adjustment of the clamping member on the under side of the arm 2 and bed plate 1 so that the jaws 7 can 100

be moved toward or away from the jaw 6 on the rotation of the screw 11. In this way the parallel edges of a rail can be rigidly clamped between them to support the arm 2 and in turn support the bed plate 1 on the under side of the rail.

The bed plate 1 has the under cut rail 13 formed integral along one side thereof and the adjustable rail 14 suitably clamped to the base on the opposite side thereof. A dovetailed channel is thus formed on top of the bed plate in which the base plate 15 of the carriage carrying the drilling mechanism is adjustably clamped in place. At the left hand end of this base 15 is hinged a second base plate 16. This second base plate overlaps the first base plate and is mounted to swing on the pin 17 supported in the lugs 18 and 19 of the first base plate. The other end of the swinging base plate has an adjusting screw 20 threaded therein. This adjusting screw passes through the swinging base plate 16 and its end rests on top of the base plate 15. On the rotation of the screw by means of the handle 21 formed on said screw the swinging base plate 16 is slowly raised at that end while the other end swings on the hinge pin 17 as illustrated in Figure 1. This is for a purpose that will presently appear.

Mounted on the top of the second base plate is the drilling mechanism proper. This mechanism comprises the bearing blocks 22 and 23. These bearing blocks are in line with each other and are suitably anchored to the swinging base plate 16. In the bearing block 23 is mounted to rotate the end of the drill spindle 24 and in the bearing block 22 is mounted to slide the sleeve 25 in which in turn is mounted to rotate the spindle 24. The sleeve 25 has a rack 26 cut into one side thereof with which the pinion 27 is adapted to mesh. The pinion 27 is mounted on the vertical shaft 28 within the bearing block 22 and adjacent to the rack 26 formed on the feed sleeve 25. To the upper end of the vertical shaft 28 is keyed the worm gear 29 which is adapted to mesh with the feed worm 30. This worm is carried on the horizontal shaft 31 which is mounted to rotate between the bearings 32 and 33 supported above the bearing block 22. On one end of the shaft 31 is mounted the feed wheel 34 and on the other end of this shaft is mounted the ratchet wheel 35 and ratchet handle 36. In this way the shaft 31 may be rotated by either the feed wheel 34 from one side of the machine or with the ratchet handle 36 from the other side of the machine. In rotating the shaft 31 and its worm 30 the sleeve 25 slowly feeds the drill spindle 24 toward or away from the web of the rail to which the machine is clamped.

The drill spindle 24 carries on the outer end a chuck 37 in which the drill 38 is held

in place. Keyed to the drill spindle 24 ahead of the bearing block 23 is the worm gear 39. This worm gear meshes with the worm 40 carried on the armature shaft 41 of the motor 42. The motor 42 is mounted on top of the swinging base plate 16 on one side of the drilling mechanism heretofore described and is adapted to rotate the spindle shaft 24 by means of the worm 40 and worm gear 39. The worm gear is splined on the spindle shaft 24. This permits the shaft to slide through the gear in order to feed the drill 38 toward or away from the web of the rail. The free end of the armature shaft is supported by the thrust bearing 43 which is also adapted to take up any thrust from the worm 40.

As heretofore pointed out the base plate 15 is mounted in the bed plate 1, being clamped in place in the dove tailed channel formed at the top thereof. For the purpose of adjusting the base plate on the bed plate the rail 14 on one side of the bed plate 1 is loosened to allow the base plate 15 to move laterally thereon. This is done by prying the base plate along the bed plate by means of a bar and is facilitated by the central row of teeth 45 formed in the bed plate between which the end of the bar can be successively inserted as the base plate 15 is moved forward on the bed plate 15. When the desired position has been reached the base plate 15 is again fastened to the bed plate by clamping it in place thereon by means of the rail 14. After the horizontal adjustment of the drilling mechanism has been made in this way it can be raised by raising one end of the swinging base plate 16 on the base plate 15. This is done by rotating the screw 20 so that the base plate 16 is lifted by it. The drill spindle 24 is thus raised to the proper height to bring it in line with the point in the rail where the hole is to be drilled. To guide the swinging base plate 16 while it is being raised or lowered on the base plate 15, a vertical post 46 is anchored on the base plate 15. This post projects through the slot 47 in the base plate 16 and keeps the two base plates in perfect alignment with each other.

The operation of the drilling machine is as follows:

The bed plate 1 is moved against the side of the rail to be drilled and is allowed to rest on the ends of the ties to which the rail is spiked. In this position the supporting arm extends under the rail between two of the ties and its jaw engages the inner edge of the base of the rail. The screw 11 is then rotated from either one side or the other side of the machine until the jaws 7, 7 formed on the outer end of the movable clamping member 5 engage the outer edge of the base of the rail. The base of the rail is thus tightly clamped between the jaws 130

6 and 7 so that the arm supports the drilling machine firmly on the rail. The lateral adjustment of the drilling machine is then made by moving the base plate 15 along 5 the bed plate 1 as above pointed out. When this is done the drilling mechanism is adjusted vertically by means of the screw 20 until the drill carried on the end of the spindle is in line with the point where the 10 hole is to be drilled in the web of the rail. The motor is then started and the drill fed toward and into the rail by means of the spindle 24. For this purpose either the hand wheel provided on one side, or the 15 ratchet handle provided on the other side of the machine may be used to regulate the feed as above pointed out.

I claim:

1. In a drilling apparatus for drilling 20 rails, the combination of a bed plate, a runway formed on top of said bed plate, a stationary jaw formed at the front of said bed plate, a movable jaw co-operating with said stationary jaw to embrace the base of 25 a rail and securely clamp said bed plate to the rail, a carriage adjustably mounted to slide in said runway parallel to the rail, a horizontal spindle mounted to rotate on said carriage, a chuck carried on the end of said 30 spindle, means adapted to rotate said spindle and means adapted to slide said spindle back and forth in said carriage during the rotation of said spindle.

2. In a drilling apparatus for drilling 35 rails, the combination of a bed plate, a runway formed on top of said bed plate, an arm projecting from said bed plate, a jaw formed on the end of said arm, said arm having a pair of holes provided therein, an adjustable 40 clamping member clamped to the under side of said bed plate, a pair of jaws formed on said clamping member, said jaws being adapted to project through and above the holes in said arm, a carriage adjustably 45 mounted in said runway, a drilling spindle mounted in said carriage and means to rotate and advance said drilling spindle in said carriage.

3. In a drilling apparatus for drilling 50 rails, the combination of a bed plate, a runway formed at the top of said bed plate, means for adjustably clamping said bed plate to the base of a rail, a carriage mounted on said bed plate and adapted to be 55 moved in said runway parallel to the rail, a spindle mounted to rotate on said carriage, and means for feeding said spindle back and forth during the rotation thereof.

4. In a drilling apparatus for drilling 60 rails, the combination of a bed plate, a runway formed at the top of said bed plate, a carriage mounted to slide in said runway parallel to the rail, guide rails overlapping a portion of said carriage, said guide rails 65 being adapted to clamp said carriage into

said runway in a predetermined position therein, a drilling spindle mounted to rotate in said carriage, clamping means provided on said bed plate, said clamping means being adapted to clasp said apparatus to 70 a rail and hold it in place thereon during the drilling operation.

5. In a drilling apparatus for drilling rails, the combination of a bed plate, a runway formed at the top of said bed plate, 75 an arm projecting from said bed plate, a jaw formed on the outer end of said arm, said arm having a pair of holes therein, a clamping member mounted to slide on the bottom of said bed plate, a pair of jaws 80 provided on said clamping member, said jaws projecting up through the holes in said arm and projecting forwardly above said arm, a lead screw mounted on the under side of said bed plate, said lead screw 85 making threaded engagement with said clamping member mounted on the under side of said bed plate, a carriage mounted in said runway on top of said bed plate, a drilling spindle mounted to rotate in said carriage, a motor for driving said drilling spindle and a train of gearing connecting said motor with said spindle.

6. In a drilling apparatus for drilling 90 holes into rails, the combination of a bed plate, a supporting arm provided on said bed plate, means for clamping said supporting arm to the rail to be drilled to support said apparatus on one side of the rail, a 95 drilling mechanism supported on said bed plate, means for adjusting said drilling mechanism laterally on said bed plate independently of said supporting arm and means for adjusting said drilling mechanism vertically on said bed plate.

7. In a drilling apparatus for drilling 100 holes into the web of rails, the combination of a bed plate, a supporting arm for said bed plate, means for clamping said supporting arm to the rail to support the bed plate alongside of the rail, a base plate mounted to slide on said bed plate, a second base plate hinged to said first base plate and adapted to swing in a vertical plane parallel 105 to the web of the rail to be drilled, a drilling mechanism mounted on said second base plate.

8. In a drilling apparatus for drilling 110 holes into the webs of rails, the combination of a bed plate, a base plate adjustably mounted on said bed plate, a second base plate hinged to said first base plate and overlapping said first base plate, a drilling mechanism carried on said second base plate, means for swinging said second base plate 115 on said first base plate to raise said drilling mechanism with relation to said bed plate, and parallel to the web of the rail to be drilled.

9. In a drilling apparatus the combina- 120

tion of a bed plate, a stationary and a movable jaw provided on said bed plate, a carriage mounted to slide on said bed plate, a supporting plate hinged to one side of said carriage, a drilling mechanism mounted on said supporting plate, said drilling mechanism being adapted to swing with said

supporting plate in a vertical plane parallel to the web of the rail to be drilled by said drilling apparatus.

10

In testimony whereof I affix my signature.

HOMER C. BOSTIAN.
